US00D439177S

(12) **United States Design Patent** (10) Patent No.: **US D439,177 S**
Fandrey et al. (45) Date of Patent: **** Mar. 20, 2001**

(54) **PRESSURE TRANSMITTER WITH SINGLE INLET BASE AND ECONOMY HOUSING**

(75) Inventors: **Mark Fandrey**, Eden Prairie; **George C. Hausler**, Maple Grove; **Steven M. Dennis**, Eden Prairie; **William J. Ballot**, New Brighton; **David A. Horky**, Mound, all of MN (US)

(73) Assignee: **Rosemount Inc.**, Eden Prairie, MN (US)

(**) Term: **14 Years**

(21) Appl. No.: **29/120,531**

(22) Filed: **Mar. 21, 2000**

(51) LOC (7) Cl. **10-04**

(52) U.S. Cl. **D10/85**

(57) **CLAIM**

The ornamental design for a pressure transmitter with single inlet base and economy housing, as shown and described.

DESCRIPTION

FIG. 1 is a perspective view;
FIG. 2 is a top plan view;
FIG. 3 is a front elevational view;
FIG. 4 is a right side view;
FIG. 5 is a left side view;
FIG. 6 is a rear elevational view; and,
FIG. 7 is a bottom plan view.
